Primary Examiner — Sandra Snapp*Assistant Examiner* — Mehri Bajoul(74) Attorney, Agent, or Firm — Lee Sullivan Shea & Smith LLP(57) CLAIM

The ornamental design for a tabletop game, as shown and described.

DESCRIPTION

FIG. 1 is a rear, perspective view of a tabletop game showing my new design;

FIG. 2 is a right-side view of my new design with the left-side view being a mirror image;

FIG. 3 is a front view of my new design; and,

FIG. 4 is a top plan view of my new design.

The evenly-dashed, broken lines depict portions of the tabletop game and form no part of the claimed design. The dot-dash lines depict boundary lines and form no part of the claimed design.
